Primary Examiner — Paula Greene(74) *Attorney, Agent, or Firm* — Samuel M. Korte; Maxwell M. Ali(57) **CLAIM**

The ornamental design for an electronic device, as shown and described.

DESCRIPTION

FIG. 1 is a front perspective view of an electronic device according to embodiments of the present invention;

FIG. 2 is a rear perspective view of the electronic device;

FIG. 3 is a top view of the electronic device;

FIG. 4 is a front view of the electronic device;

FIG. 5 is a bottom view of the electronic device;

FIG. 6 is a rear view of the electronic device;

FIG. 7 is a left side view of the electronic device; and,

FIG. 8 is a right side view of the electronic device.

Portions of FIGS. 1 through 8 are shown in dashed lines for illustrative purposes only and form no part of the claimed design.

1 Claim, 3 Drawing Sheets
